Primary Examiner — Cynthia R Underwood*(74) Attorney, Agent, or Firm* — Edell, Shapiro & Finn, LLC(57) **CLAIM**

The ornamental design for a underwater hook, as shown and described.

DESCRIPTION

FIG. 1 is a front view of a hook according to the present invention;

FIG. 2 is a rear view of the hook of FIG. 1;

FIG. 3 is a right side view of the hook of FIG. 1;

FIG. 4 is a left side view of the hook of FIG. 1;

FIG. 5 is a bottom view of the hook of FIG. 1;

FIG. 6 is a top view of the hook of FIG. 1;

FIG. 7 is a front perspective view of the hook of FIG. 1;

FIG. 8 is a front view of a hook according to a second embodiment of the present invention;

FIG. 9 is a rear view of the hook of FIG. 8;

FIG. 10 is a right side view of the hook of FIG. 8;

FIG. 11 is a left side view of the hook of FIG. 8;

FIG. 12 is a bottom view of the hook of FIG. 8;

FIG. 13 is a top view of the hook of FIG. 8; and,

FIG. 14 is a front perspective view of the hook of FIG. 8.
